UNITED STATES PATENT OFFICE.

FRANK W. LINSTROMBERG, OF BOURBON, MISSOURI.

LAMP-CHIMNEY HOLDER.

1,171,796.

Specification of Letters Patent. Patented Feb. 15, 1916.

Application filed March 15, 1915. Serial No. 14,499.

To all whom it may concern:

Be it known that I, FRANK W. LINSTROMBERG, a citizen of the United States, residing at Bourbon, in the county of Crawford and 5 State of Missouri, have invented certain new and useful Improvements in Lamp-Chimney Holders, of which the following is a specification.

My invention relates to lamps, and more 10 particularly to improvements for securing a lamp chimney in position adjacent the burner.

The primary object of my invention is to provide a simple, cheap, and durable 15 clamping band for assisting in the retention of a lamp chimney in position.

A further object of my invention is to provide a device of the above mentioned character which may be easily and quickly 20 placed in position, and one which is readily removable and applicable to almost any size of lamp.

A still further object of my invention is to provide an improved clamping means as- 25 sociated with the retaining band which facilitates the convenient disposal and reten- tion of the device on a lamp chimney for the purpose set forth.

A still further object of my invention is 30 to provide means associated with the clamping member which will automatically lock the same against accidental dislodgment from clamped position.

With the above and other objects in view 35 my invention resides preferably in the construction, combination, and arrangement of parts as hereinafter set forth in the specification and illustrated in the accompanying drawing, in which—

40 Figure 1 is a side elevation of a lamp burner and chimney showing my improved retainer in position. Fig. 2 is a top plan view of the same, the lamp chimney being shown in section and my invention being 45 fragmentarily indicated. Fig. 3 is a plan view of the improved clamping member. Fig. 4 is a longitudinal sectional view taken on the line 4—4 of Fig. 3. Fig. 5 is a trans- 50 verse sectional view taken on the line 5—5 of Fig. 3.

Similar reference characters indicate simi- 5 lar parts throughout the various views of the drawings.

In the drawings the numeral 1 indicates the base of an ordinary lamp burner 2, the 55 said lamp burner 2 having the usual resilient arms 3 extending vertically therefrom for embracing the base 4 of the ordinary lamp chimney, glass or otherwise.

My improvement is adapted for use in 60 conjunction with the usual retaining arms 3 and comprises a resilient band, this band be- 65 ing in the present instance shown as a helical spring 5 extending substantially completely around the base 4 of the lamp chimney and 70 adapted to inclose in its embrasure the re- 75 sident arms 3. The opposite extremities of the band 5 are connected, respectively, to the movable and stationary elements of my clamping member, described in detail here- 80 after. I have found that the disposition of the band 5 as shown in Fig. 1 is preferable, 85 since this is approximately the point at which the arms 3 usually engage the chimney base 4.

My improved clamping device comprises a strip of bendable metal 6 having the mar- 90 ginal edges bent to form longitudinally dis- 95 posed and laterally extending flanges 7 and 8, forming as a whole a channel member. 80 The strip 6 is extended as at 9 and aper- 95 tured as at 10 for reception of one extrem- 100 ity of the band 5 which is preferably formed with a loop 11 for engagement in the aper- ture 10. The strip 6 is provided adjacent 85 its opposite extremity with an elongated aperture 12. Upon reference to Fig. 4, it will be noted that a portion of the strip 6 is depressed from the plane of the main por- 90 tion of the strip 6 as shown at 13 to pro- 95 vide a guide or runway for the spring 5, this function being brought out more fully herein- 95 after. Owing to this peculiar forma- 100 tion, it will be noted that the flanges 7 and 8 converge slightly as indicated at 14 which 95 performs a function which will be herein- after set forth. A pivoted lever is provided which comprises a strip or plate 15 of bend- able metal, said plate 15 having a pair of 100 oppositely extending lateral projections 16

and 17 on one extremity thereof, said projections 16 and 17 forming spindles or pivots for the plate or lever 15 and being receivable in suitable apertures 18 provided in the flanges 7 and 8 of the strip 6. The free extremity of the plate 15 is enlarged as shown at 19 and outwardly bent as at 20 to provide a handle.

Upon reference to Fig. 5 it will be noted that the width of the plate 15 is such that the same when in locked position will snugly engage the flanges 7 and 8 for a purpose which will hereinafter appear. The inner extremity of the plate 15 is recessed as shown at 21, to receive the portion of the band 5 which is adapted to lie therein when the device is in clamped position. One extremity of the band 5 being secured to the extension 9, the opposite extremity thereof is then secured to the arm 15 at a point substantially intermediate its length, this extremity of the band 5 being looped as shown at 22, and the plate 15 being provided with a struck-up portion 23 for engagement with the loop 22, as shown to advantage in Figs. 3 and 4.

In order to lock the arm 15 in clamped position, the flanges 7 and 8 are depressed inwardly from their outer marginal edges to provide locking abutments 24, which owing to the inherent resiliency of the material utilized will allow of reception of the arm or lever 15 between the flanges 7 and 8, to allow for a tendency to prevent its withdrawal from all accidental sources.

From the above description taken in connection with the accompanying drawings, it is thought that a clear and comprehensive understanding of the construction, use, and advantages of my invention may be readily gathered. In use the base 4 of the lamp chimney is placed in position in the usual manner, and the resilient band 5 slipped over the top of the same and moved into the position shown in Fig. 1. During this operation the lever 15 should be in a released position indicated in dotted lines at 25 in Fig. 4. When the lamp chimney has been disposed in position and the band in its respective position, the arm 5 is moved into the clamping position shown in the drawings until the marginal edges thereof engage under the locking abutments 24, and at this time it will be found that the lamp chimney is rigidly held in position. Accidental vibration or other movements of the clamping mechanism will not dislodge the same owing to the engagement of the arm 15 with the locking abutments 24. When in clamped position it will be readily understood that the band 5 is in the distended position so that at all times secure clamping engagement with the arms 3 is afforded and that accidental dislodgment of the lamp chim-

ney is practically impossible under ordinary conditions. I desire to lay particular stress on the peculiar construction of the clamping member, and while I have shown the invention as applied to the function of retaining a lamp chimney in position, it will be readily understood that the scope of its uses is not limited.

When the device is in locked position, the spring 5 will be received on the runway 13, which, owing to its peculiar formation, will prevent accidental dislodgment of the spring. Should the same become dislodged from any reason, the flanges 7 and 8, converging as at 14 will have a tendency to return the spring to the position shown.

While I have shown and described my invention as possessing a peculiar form and construction, it is desired that it be understood that I may make such changes in the details thereof that do not depart from the spirit and scope of the invention as claimed.

Having thus described my invention what I claim and desire to secure by Letters Patent is:

1. A lamp chimney holder, including a resilient band, a clamping member comprising a channel, a lever pivoted therein, the extremities of said band being connected to the channel and lever, and means in said channel to retain said lever in clamped position.

2. A lamp chimney holder, including a channel member having a lever pivoted on the walls thereof, a resilient band having one of its extremities connected to the channel member and the other extremity connected to the pivoted lever, said channel member having the walls thereof provided with locking abutments for engagement with the lever, as and for the purpose set forth.

3. A lamp chimney holder, including a resilient band, a clamping member comprising a strip of bendable metal having the marginal edges bent to form longitudinally extending lateral flanges affording a channel structure, a lever pivoted to said channel structure and of such a width as will facilitate its snug reception in the channel member, the opposite extremities of said resilient band being associated with the flanged strip and the lever, and locking abutments formed on the said lateral flanges by depressing the same inwardly, as and for the purpose set forth.

4. A lamp chimney holder, including a resilient band, a strip of bendable metal having the marginal edges formed to provide longitudinally extending lateral flanges, a lever pivoted on said flanges and snugly receivable therebetween, the extremities of said band being secured to said lever and said strip, respectively, depressions formed on the flanges and projecting inwardly to provide locking abutments for engagement with

the marginal edges of the lever when in clamped position, and guide means for the said resilient band associated with said strip.

5. A lamp chimney holder comprising a channel member, a lever pivoted in said channel member, a resilient band having its extremities connected to the channel and le-

ver respectively, and friction means for retaining said lever in clamping position. 10

In testimony whereof I affix my signature in presence of two witnesses.

FRANK W. LINSTROMBERG.
